GARMENT HANGER

Robert C. Heffernan, Great Neck, N. Y.

Application May 17, 1947, Serial No. 748,720

7 Claims. (Cl. 223—91)

1

The present invention relates to garment hangers and is more particularly directed toward garment hangers each of which is adapted to act as a coat hanger, a trousers or skirt hanger, and/or a hanger for slips, corsets and the like having shoulder straps.

The present invention contemplates a garment hanger preferably made of two pieces of wire or rod. These are bent to a suitable configuration and secured together in such a manner as to provide, firstly, a coat hanger with its outer ends widened so as to provide wide bearing areas for the shoulder portion of a coat or the like—secondly, a spring clip-like arrangement whereby a flat garment such as the waist of a skirt or the bottoms of trouser legs may be securely gripped so as to hang the skirt or trousers—and thirdly, hook elements capable of supporting lingerie hanging from the usual shoulder straps.

According to the present invention it is possible to make garment hangers suitable for these purposes in an inexpensive manner and yet provide a rugged and serviceable article for the purposes.

The accompanying drawings show, for purposes of illustrating the present invention, an embodiment in which the invention may take form, it being understood that the drawings are illustrative of the invention rather than limiting the same.

In these drawings:

Figure 1 is a perspective view of the hanger looking at it from one side;

Figure 2 is an inverted plan view of the hanger of Figure 1; and

Figure 3 is a side elevational view illustrating the use of the hanger in supporting a skirt or pair of trousers.

The construction shown herein employs two pieces of bent resilient wire, preferably steel wire or light rod stock. In the drawings the diameter of the wire is exaggerated.

The construction shown herein employs two identical bent wire members one of which is marked A and the other B, and a hook C. The members A and B have ring-like upper ends 10—10' through which the hook C may be passed. The wire member A has a straight downwardly sloping portion extending to the point marked 11 where the wire bends outwardly as indicated at 12. The wire then extends downwardly as indicated at 13 in a plane to one side of the plane of the portion 10—11. The wire is then bent as indicated at 14 and extends horizontally as indicated at 15 to point 16 which is approximately below the bend between the parts 12 and 13. It

2

is then bent inwardly as indicated at 17 to bring it back to the plane of the portion 10—11. The wire then extends across from the point 18 to 19 where it is bent as indicated at 20 to provide a configuration similar to that at 17 where it then extends horizontally as indicated at 21, is bent as indicated at 22 and then extends upwardly and inwardly as indicated at 23 and is bent back as indicated at 24 so as to be again in the same plane as the portion 10—11. The wire piece A then extends upwardly as indicated at 25 and is provided with a bent hook 26. The wire B has the same configuration as the wire A and the same reference characters are applied to this wire element with a prime added, in so far as possible in the drawings.

The portions 25 and 25' of the wires A and B lie alongside the downwardly extending portions of the other wire member and these wire members are welded together as indicated at 27—27 at the left of Figure 1. Similar welding occurs on the right hand side of the hanger.

The wire members A and B are so manufactured that when they are welded together as indicated and the hook ends secured to one another, for example by the hanger supporting hook C, there is provided a strong rigid structure well shaped for the support of garments. The portions 13, 23' and 13', 23 provide wide areas for the support of the shoulder portions of the coat. The inherent resiliency of the wire members holds the straight central parts 18—19, 18'—19', in contact with one another. Owing to the fact that the parts 13 and 15 of one wire member are spaced from the parts 21', 23' of the other member, and the construction is similar at the other end, space is provided for the insertion of the cuff or waistband of the skirt between the wire members and into the clip or clasp formed by the central portions 18—19, 18'—19'. Such a garment can be slid into position as indicated in dotted lines in Figure 3 and will be securely gripped by the inherent resiliency of the parts.

The hooks 26—26' are available for hanging lingerie or other accessories.

While the present design utilizes two identical pieces of wire welded together to form the body of the hanger, it is, of course, to be understood that various other arrangements of wires may be employed to provide a hanger in which the widened areas are available for the support of the shoulder of the coat and the clip is available to support flat garments such as trousers or skirt. Hence any other arrangement of wire parts to occupy positions in the finished structure equiv-

alent to positions occupied in the illustrated construction could function in the same manner.

What is claimed is:

1. A garment hanger made of two pieces of wire, each bent to isosceles triangular shape in side elevation, except that one side falls short of reaching the apex of the triangle so as to leave an opening, the two pieces being fixedly secured together so that the apex portion of one bridges the opening formed by the other, means to secure the pieces together at the apex, the pieces forming a spring clip wherein the triangle bases are urged toward one another to grip a garment inserted therebetween.

2. A garment hanger as claimed in claim 1, wherein the outer portions of the sides and bottom are spread apart to provide widened areas for supporting the shoulder portions of a coat.

3. A garment hanger as claimed in claim 1, wherein each wire forming the shorter side of the triangle has a hook at its upper end for support of lingerie.

4. In a garment hanger, two wire members having side by side bottom elements the central portions thereof close together and the outer portions thereof spaced, the members then extending upwardly and inwardly at substantially the same spacing and then being secured to one another, the inwardly sloping spaced portions providing a widened area for support of the shoulder portion of a garment, the closely spaced central portions providing a narrow space to receive a flat garment.

5. A garment hanger made of two pieces of resilient wire bent to shape to provide at each side downwardly and outwardly sloping end portions and transverse bottom portions extending from side to side, of a general contour to receive

and support a coat, and secured together at the upper part of each side portion, the lower parts of the end portions being spaced laterally from one another to provide added width to receive the shoulder portions of the coat, the bottoms being closer to one another and urged toward one another by the resiliency of the end portions so as to grip a flat garment inserted therebetween.

6. A garment hanger as claimed in claim 5, having hooks above the points of securement of the wire members to one another for the support of lingerie.

7. A garment hanger having ends sloping downwardly and outwardly from an apex and two horizontal bottom interconnecting portions, the bottom portions and the lower portions of the ends being composed of two resilient members secured together near the apex, and the portions of the members along the lower parts of the ends of the hanger and the outer parts of the bottom portion of the hanger being spaced apart to provide a widened region for supporting the shoulder portions of a garment, the interconnecting central parts of the bottom portions of the hanger being urged toward one another to grip a garment inserted therebetween.
